UNITED STATES PATENT OFFICE.

CHARLES H. DE FREHN, OF JOHNSTOWN, PENNSYLVANIA.

SANITARY TRAY.

1,226,866.

Specification of Letters Patent. Patented May 22, 1917.

Application filed October 31, 1916. Serial No. 128,768.

To all whom it may concern:

Be it known that I, CHARLES H. DE FREHN, a citizen of the United States, residing at Johnstown, in the county of Cambria and State of Pennsylvania, have invented a new and useful Sanitary Tray, of which the following is a specification.

The device forming the subject matter of this application is a tray for a high chair, and one object of the invention is to provide novel means for connecting the tray pivotally with the tray supports, and for holding the tray in a horizontal position with respect to the supports.

Another object of the invention is to provide novel means for assembling with the tray supports, a pair of side strips between which the tray fits.

The invention aims, generally, to provide a high chair tray which can be cleaned out readily.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—

Figure 1 shows in perspective, a portion of a high chair equipped with the device forming the subject-matter of this application;

Fig. 2 is a transverse section taken through the tray from the back of the tray toward the front of the tray, parts of the chair proper appearing in elevation;

Fig. 3 is a vertical section taken approximately on the line 3—3 of Fig. 1;

Fig. 4 is a fragmental top plan of the tray and attendant parts, portions being broken away, the view depicting a slight modification in the invention.

In Figs. 1 and 2 of the drawings there is shown a part of a high chair including a back 1 having arms 2. Supports 3 are shown, the same being pivoted at 4 to the back 1. Intermediate their ends, the supports 3 are connected by a rod 5 having nuts

6 or the like at its ends, the nuts engaging the outer faces of the supports 3. The rod 5 prevents the supports 3 from spreading apart.

The numeral 7 designates, generally, a tray. In Fig. 2, the tray is shown as comprising a bottom 8, a front bar 9 secured to the bottom, and a rear bar 10 secured to the bottom. There is nothing to prevent the tray being manufactured in one piece, if desired. The bars 9 and 10 upstand above the bottom 8 of the tray, and the tray, therefore, may be described as being in the form of a trough which is open at its ends. In the rear face of the bar 10 there is formed a recess 11 extended from one end of the bar to the other end and defining a shoulder 12.

Mounted in the supports 3 near to their outer ends, are pivot elements 14 of any desired sort. The pivot elements 14 enter the ends of the front bar 9 of the tray 7, and thus the tray is mounted for vertical swinging movement. The shoulder 12 rests on the rod 5, and thus the tray is held in a horizontal position between the supports 3.

Applied to the inner faces of the supports 3 are side strips 15 which preferably are made of metal. The side strips 15 have beads 16 at their upper edges, which overhang and engage the upper edges of the supports 3. The rod 5 passes through the rear ends of the side strips 15, and the pivot elements 14 pass through the forward ends of the strips 15. In this manner, the strips 15 are held on the supports 3. The side strips 15 lie at the end of the trough-shaped tray 7, and constitute closures for the ends of the tray.

The tray 7 may be swung upwardly and forwardly, and thus material which has accumulated within the tray may be dumped out, or the material may be wiped out through the ends of the tray, when the tray rises above the side strips 15. The side strips 15 serve to prevent the supports 3 from being marred by the ends of the tray 7, when the tray 7 is swung upwardly and downwardly. The rod 5 acts not only as a stop for holding the tray 7 in a horizontal position, but serves, also, to prevent the supports 3 from spreading apart. When the tray 7 is in a lowered position, the tray rests on the arms 2. The nuts 6 may be tightened up so that the supports 3 bind the strips 15 against the ends of the tray 7. In this manner, tight joints are afforded, and, at the

same time, the tray 7 is prevented from swinging upwardly on the pivot elements 14 when the tray rests on the arms 2, as shown in Fig. 2.

5 It will be understood that beads 16 on the side strips 15 may be constructed as desired, depending upon the nature of the finish which the strips 15 are to have at their upper edges.

10 In Fig. 4 of the drawings, wherein a slight modification in the invention appears, parts hereinbefore described have been designated by numerals formerly used, with the suffix "a." In this form of the invention, the 15 pivot elements 14^a engage the rear bar 10^a of the tray 7^a, whereas the front bar 9^a has a shoulder 12^a which engages the rod 5^a, the latter being mounted in the forward ends of the supports 3^a. Essentially, the difference 20 between that form of the invention shown in Fig. 4, and the form shown in Fig. 2, is that, in Fig. 2, the tray is mounted to swing forwardly, whereas in Fig. 4, the tray swings rearwardly.

25 Having thus described the invention, what is claimed is:—

30 1. In a device of the class described, supports; a tray disposed between the supports and in the form of a trough which is open at its ends, the supports constituting 35 closures for the ends of the tray; means for pivoting the tray adjacent one of its edges to the supports; and stop means coacting with the tray to hold the same between the supports, whereby the supports will constitute 40 closures for the ends of the tray.

45 2. In a device of the class described, supports; a tray disposed between the supports and in the form of a trough which is open at its ends, the supports constituting closures

for the ends of the tray; means for pivoting the tray adjacent one of its edges to the supports; and a rod connecting the supports, the opposite edge of the tray resting on the rod.

45 3. In a device of the class described, supports; a tray disposed between the supports; means for pivoting the tray adjacent one of its edges to the supports; a rod connecting the supports, the opposite edge of the tray resting on the rod; and a tightening device on the rod and engaging one support, to cause the supports to bind against the ends of the tray.

50 4. In a device of the class described, supports; a tray disposed between the supports; pivot elements connecting the tray adjacent one of its edges to the supports; a rod connecting the supports and coacting with the opposite edge of the tray to uphold the 55 tray; and side strips interposed between the supports and the ends of the tray, the side strips being carried by the pivot elements and the rod.

55 5. In a device of the class described, supports; a tray disposed between the supports; pivot means connecting the forward portion of the tray with the supports; stop means carried by the supports and engaging the tray adjacent its rear edge; and side strips 70 interposed between the supports and the ends of the tray, the side strips being carried by the pivot means and the stop means.

60 In testimony that I claim the foregoing as my own, I have hereto affixed my signature in the presence of two witnesses.

75 CHARLES H. DE FREHN.
